UNITED STATES PATENT OFFICE.

ALBERT BEZNER, OF RAVENSBURG, GERMANY.

SORTING-MACHINE.

1,126,359.

Specification of Letters Patent. Patented Jan. 26, 1915.

Application filed February 4, 1913. Serial No. 746,177.

To all whom it may concern:

Be it known that I, ALBERT BEZNER, a citizen of the German Empire, and residing at Ravensburg, Wurttemberg, Germany, have invented certain new and useful Improvements in Sorting Machines, of which the following is a specification.

My invention relates to a swing sorting machine for sorting or screening both dry material, *e. g.* the disintegrated wood for cellulose manufacture, and also wet or liquid-like materials, *e. g.* wood particles suspended in water, cellulose, or paper-pulp.

The new sorting machine operates similarly to the flat sifter well known in the milling trade, *i. e.* by means of a swinging motion given to the sorting chest. Owing to this swinging motion the material while being sorted is given a motion over the sieves or toward them of a loop-like form, while propelling boards or metal plates give a continual forward movement to the said material.

The novelty of my invention consists in the provision of a sorting chest which is of ring form, the ring being either round or of any other desired shape. The driving arrangements of my swing sorting machine are arranged in the space inclosed by the ring-like chest. By locating the driving mechanism in this space it is possible to apply in known manner the driving power directly at the level of the center of gravity of the chest. When admitted, the material to be sorted is divided by means of one or more vertical partitions into two, four or more parts, half of which parts runs through the one half, and half of which parts runs through the other half of the sorting chest, the material of each grade having a common outlet located at a part of the ring opposite the inlet. The advantage so obtained is that large quantities of the material to be sorted can be dealt with in a comparatively small machine.

Owing to the crank-pin being applied at the level of the center of gravity, my machine differs from the known flat sifters in that it is not necessary to construct double sifters with completely separated points of ingress and egress. Because the sorting chest is accessible from all sides, small, individually exchangeable sieves can be employed. My new sorting machine moreover gives the advantage of compact construction, in that the mechanism for suspending or support-

ing and driving the sorting chest becomes very much simplified. Concerning the other features of the sorting machine, in particular concerning the arrangement in these machines of the vertical sorting walls designed for use with wet material requiring sorting, and concerning the special means effecting the transmission of motion, detailed particulars will be hereinafter given.

Several illustrative embodiments of my invention are represented by way of example in the accompanying drawings, wherein:

Figures 1 to 3 relate to the first form of sorting machine; of these figures Fig. 1 is a side elevation partly in section, Fig. 2 a plan, also partly cut away and Fig. 3 a sectional view showing the suspension device for the chest; Figs. 4 and 6 relate to a second form of sorting machine; of these figures Fig. 4 is a side elevation partly in section, Fig. 5 a vertical section of the admission chamber for the material to be sifted and Fig. 6 a plan of said chamber; Figs. 7 and 8 relate to a third form of sorting machine, Fig. 7 being an elevation partly in section and Fig. 8 a plan partly in section; and Figs. 9 and 10 relate to a fourth form of sorting machine, Fig. 9 being a vertical section and Fig. 10 a horizontal section on the line A—B in Fig. 9.

Referring to Figs. 1 and 2, 1 is the frame of the sorting machine, this frame journaling the shaft 2 carrying the flywheel 3. The crank pin 4 fast on the flywheel engages in a cross 5 around which the sorting chest 6 is rigidly mounted in such a way that the horizontal plane containing the center of gravity of the chest transversely bisects the pin 4. In the corners formed by the inside walls 7 of the sorting chest are located corner-brackets 8 carrying bearings 9 for the lower ball-ended pins 10 of the suspensions 11 (see Fig. 3). Mounted on the frame 1 are four columns 12 carrying, rigidly fixed at their upper ends, the second cross 13. The four corners of this cross 13 run out into brackets 14 carrying the bearings 15 (Fig. 3) for receiving the ball-ended pins 16 of the suspension 11. The sorting chest has four vertical inside walls 7, four vertical outside walls 17, a bottom 18 and a cover 19, as well as the sliding sieve-frames 20, 20'. The sieve-frames 20 have a larger mesh than the sieve-frames 20'. The admission chamber 22 for the sorting chest

6 is subdivided by means of the partition 23. One half of this chamber is arranged to lead the material along the track 26 of the sieve-frame 20, the other half to lead it along the track 27 of the sieve-frame 20. There are also arranged, in each case to suit the direction of rotation, propelling blades 24 and 25, the former in one half of the chest on the inside walls 7 and the latter in the other half on the outside walls 17. From the admission chamber 22 the two tracks 26, 27 run over the sieve 20 to the outlet 28. The outlets are so arranged that the various grades of the sorted products remain separated one from another, the same grade of product from the same sieves issuing however together at 28, 29 or 38. The shaft 2 is driven by means of the pulley 30, and the motion is transmitted by the crank-pin 4 and the cross 5 to the entire sorting chest 6, which is thus given a circular swinging motion with corresponding pendulous motions of the suspensions 11. The material being sorted is moved forward in the tracks 26, 27 on the sieve 20 by means of the propelling blades 24 or 25 to the outlet 28, only the coarsest grades thus reaching this outlet 28; on the other hand the grades of medium fineness together with the finest grades fall onto the sieve 20'. Of the material covering the sieve 20' the grades of medium fineness reach by means of corresponding propelling blades in the two tracks, the outlet 29. The finest grades which have fallen through the sieves 20, 20' are thus completely separated from the remaining constituents of the original material.

The second form of machine, as illustrated in Figs. 4 to 6, differs from the above described solely in that the admission chamber has two cross partitions 23, 23' and therefore four inlets 31, 32, 33, 34 separated one from another. Moreover two sorting chests 6, 6' are arranged one over the other, each being provided with two sieves 20, 20', 20'', 20''. Here the sieves 20, 20' have the same mesh, and likewise the sieves 20', 20''. The material to be sorted passes into the inlets 31, 32, 33, 34 of the common admission chamber 22, and half of it thus passes to the two separate tracks on the sieve 20, and the other half to the two separate tracks on the sieve 20''. The two halves of the material being sorted are then sorted out in the same manner as in the first form of machine described and the products of the same fineness are led together to the same outlets. What remains above the sieves 20, 20'' issues at the outlets shown at the left of Fig. 4, while what remains above the sieves 20', 20'', issues at outlets at the rear which are not shown in Fig. 4. The finest product after falling through the sieves 20' and 20'' reaches the outlets 36, 36' in the common junction-pipe 37. Of course junc-

tion-pipes may also be provided for the other pairs of outlets.

The form of machine just described indicates that by providing a suitable number of partitions in the admission chamber the whole of the material to be sorted can be divided in a desired manner, and particularly that the said material can be distributed instead of on one or two, also on several, sieves of the largest mesh and from these can be sorted by means of several sieves of continually diminishing grades of fineness.

The third form of sorting machines differs from that described with reference to Fig. 1 in that the sorting chest is not held by suspensions but rests on balls running in grooves. The swinging motion of the sorting chest is here given by cams, and a vertical driving shaft can be so dispensed with. As Figs. 7 and 8 show, the driving shaft 41 having thereon a belt pulley 40 carries at each end an eccentric 43 running in an oil-box 42. Owing to the rotation of the eccentrics, the oil-boxes are driven to and fro in directions transverse to the axis of rotation. Since however those outer surfaces of the eccentrics which are radial to the said axis are not in a rectilinear plane at right angles thereto, the abutment pieces 44 acting on these surfaces simultaneously give to the oil-box 42 a to-and-fro motion in directions at right angles to those of the motions just described. It is evident that a motion dependent upon the coöperation of the two eccentric motions and on the form of the eccentrics can be obtained which differs in desired manner from a circular motion. This is a consideration of importance in the wet sorting machine hereinafter described. The oil-boxes 42 are supported on balls 39 (Fig. 7) which run in grooves 50.

The fourth form of sorting machine, as illustrated in Figs. 9 and 10, differs from those hereinbefore described in being suitable not for dry but for wet material and in having not horizontal but vertical sieve-walls. As seen in Figs. 9 and 10, 6 is the ring-shaped sorting chest which has the divided admission chamber 22. Inside the sorting chest are arranged the two ring-shaped, unperforated bottom-plates 45, 45' which are bounded outwardly by the vertical sorting surfaces or sieves 46, 46'. In order to conduct the material passing through the sieve 46 to the bottom-plate 45', the inclined guide-plate 47 is arranged above the sieve 46'. Each bottom-plate 45, 45' has a suitable channel 48, 48' which conducts the material coming onto it back again to the place of admission before it is subjected to the action of the propelling blades 24, 24'. Above the bottom-plates 45, 45' are arranged the water-shower pipes 49, 49'. Their purpose is to replace the water

flowing off during the sorting operation. The wet sorting machine described is especially suitable for liquids containing bodies in suspension, such as *e. g.* wood-meal, cellulose and so forth. Such liquid first falls on the unperforated bottom-plate 45, and receives with this plate a swinging motion, it is thus thrown by the propelling blades 24 against the walls of the sieve 46, 10 and so sorted that the coarsest particles remain behind in the upper, while the finest flow away to the lower part of the machine. That portion of the material being sorted which has penetrated the uppermost sieve 15 falls into the inclined channels 48, and, when arriving close to where it was admitted, falls from these channels onto the inclined plate 47 in order to be again subjected to the action of the propelling blades (in this case 20 24'). The finest particles of the material being sorted penetrate the sieve 46, reach the channel 48', and, when near the place of admission, pass to the propelling blades 24'', in order to finally leave the sorting 25 chest at 38.

I claim:—

1. In a swing sorting machine, the combination of a frame, a sorting chest of ring form, supported by said frame and provided 30 with sieve-frames, said chest having an inlet and an outlet, said outlet being removed from said inlet, two tracks of said sieve-frames leading from said inlet to said outlet, means mounted in said frame for oscillating said chest.

2. In a swing sorting machine, the combination of a frame, a sorting chest of ring form, supported by said frame and provided with sieve-frames, said chest having 40 an inlet and an outlet, said outlet being removed from said inlet, two tracks of said sieve-frames leading from said inlet to said outlet, means mounted in said frame for applying a driving force to said chest substantially at the level of the center of gravity thereof and within the central space inclosed by said chest and oscillating said chest, and propelling blades secured in said sorting chest.

3. In a swing sorting machine, the combination of a frame, a sorting chest of ring form supported by said frame, said chest having an admission chamber at one part thereof and a plurality of compartments located 50 one above the other and each provided with an outlet at a part of the chest located opposite the part having the said admission chamber, a vertical partition bi-secting said admission chamber, and radially arranged 55 in said chest, means mounted in said frame for oscillating said chest, and propelling blades secured in said sorting chest.

4. In a swing sorting machine, the combination of a frame, a sorting chest of ring form supported by said frame, said chest 65 having an inlet, an outlet, and partition walls comprising an unperforated floor, and a vertical sieve at the periphery of said floor, means mounted in said frame for oscillating said chest, and propelling blades secured 70 in said sorting chest.

5. In a swing sorting machine, the combination of a frame, a sorting chest of ring form supported by said frame, an admission chamber and a plurality of compartments 75 within said chest located one above another and each provided with an outlet, said compartments having partition walls comprising an unperforated floor and a vertical sieve at the periphery of said floor, means 80 mounted in said frame for oscillating said chest, and propelling blades fast in each of said compartments, the compartments below the admission chamber, each having an inclined plate extending from the wall of the 85 chest downwardly to said propelling blades.

6. In a swing sorting machine, the combination of a frame, a sorting chest of ring form supported by said frame, said chest 90 having an admission chamber and a plurality of compartments located one above another and each provided with an outlet, said compartments having partition walls comprising an unperforated floor and a vertical sieve at the periphery of said floor, 95 means for leading the material to the inlet of the next compartment after said material has passed through each said sieve, means mounted in said frame for oscillating said chest and propelling blades fast in each of 100 said compartments.

7. In a swing sorting machine, the combination of a frame, a sorting chest of ring form supported by said frame, said chest 105 having an admission chamber and a plurality of compartments located one above another and each provided with an outlet, each compartment above the lowest being divided by a vertical sieve into a sifting compartment and a returning compartment, 110 the latter having an unperforated floor provided with an opening leading into the compartment below and being inclined toward such opening, means mounted in said frame for oscillating said chest and propelling 115 blades in each of said sifting compartments and in the lowest compartment.

In testimony whereof I affix my signature in the presence of two witnesses.

ALBERT BEZNER.
